UNITED STATES PATENT OFFICE.

WILLIAM ALLEN MITCHELL, OF EAST ST. LOUIS, ILLINOIS.

DRAFT-REGULATING DEVICE.

1,337,786.

Specification of Letters Patent. Patented Apr. 20, 1920.

Application filed August 23, 1919. Serial No. 319,383.

To all whom it may concern:

Be it known that I, WILLIAM ALLEN MITCHELL, a citizen of the United States, residing at East St. Louis, in the county 5 of St. Clair and State of Illinois, have invented certain new and useful Improvements in Draft-Regulating Devices, of which the following is a specification.

This invention relates to new and useful 10 improvements in draft regulating devices, while not necessarily limited to this use.

An important object of the invention is to provide means for holding chains, draft regulating devices, and the like in a given position. 15

A further object of the invention is to provide such holding means which will not require release of the chain before changing the position thereof.

Other objects and advantages of the invention will be apparent during the course 20 of the following description.

In the accompanying drawings forming a part of this specification and in which like numerals are employed to designate like 25 parts throughout the same,

Figure 1 is a side elevation of an apparatus embodying my invention,

Fig. 2 is a vertical section therethrough, 30 Fig. 3 is a front elevation, the chain wheel and spring being removed for the purposes of clarity, and,

Fig. 4 is a perspective of the upper end 35 of the spring.

Referring now more particularly to the drawings, the numeral 10 indicates a plate provided with openings 11 and 12 by means of which the plate may be secured to a suitable support. The plate is provided upon 40 its upper end with outstanding flanges 13 and 14, each of which has formed therein an opening 15 adapted to receive a shaft 17.

Mounted upon the shaft 17 is a chain wheel 18 about which is passed a chain 19.

The body of the plate 11 is provided approximately centrally thereof with an outstanding portion 20 having a central depression 21. Adjacent its lower end, the plate 10 is provided with a support 22, to

which is secured by means of screws 23 or 50 the like, a spring 24. The upper end of the spring 24 is bent outwardly and provided upon the face of the bend with a lug 25. This lug normally seats in the depression 21 formed in the outstanding portion 20 of 55 the plate 10.

The chain 19 passed about the wheel 18 extends intermediate the outstanding portion 20 and the spring 24, and the lug 25 of this spring is adapted to engage in the 60 links thereof. It will be readily seen that the engagement of the lug in the link would prevent normal displacement of the chain 19, and that if the chain 19 is firmly grasped, it may be moved in either direction because 65 of the resiliency of the locking member.

While my device is primarily intended for use as a means for regulating the draft of stoves, furnaces and the like, it will be readily seen by those familiar with the art 70 that it is capable of extended use wherever an adjustable chain control is used.

It is to be understood that the form of my invention herewith shown and described is to be taken as a preferred example of the 75 same, and that various changes in the shape, size, and arrangement of parts may be resorted to without departing from the spirit of the invention or the scope of the subjoined claim.

Having thus described my invention, I 80 claim:

In a device of the type described, a plate having a shallow depression formed therein, a spring secured to said plate and a 85 chain passing intermediate said depression and said spring, said spring holding said chain in contact with the base of said depression, said chain being shiftable in either direction while engaging the base of said 90 depression under the action of said spring.

In testimony whereof I affix my signature in presence of two witnesses.

WILLIAM ALLEN MITCHELL.

Witnesses:

W. H. KELLEY,
SOL ANTIBIS.
